UNITED STATES PATENT OFFICE.

ERNST FRIEDRICH WILHELM MÜLLER, OF BERLIN, GERMANY.

CAR-BRAKE.

SPECIFICATION forming part of Letters Patent No. 322,959, dated July 28, 1885.

Application filed February 12, 1885. (No model.)

To all whom it may concern:

Be it known that I, ERNST FRIEDR. WILHELM MÜLLER, of the city of Berlin, Kingdom of Prussia, German Empire, have invented a new and useful Improvement in Brakes, of which the following is a specification.

The rapidly-acting brake to which this invention relates has for its object to enable vehicles, and more especially tramway and railway cars, to be rapidly stopped in cases of emergency where the usual brakes would not act with sufficient promptness, without, however, interfering with the use of the brakes to be operated by hand. The construction of this brake is such that—say on a tram-car—the driver may instantaneously stop the car by throwing a pawl of the brake device out of engagement by a movement of his foot. The said brake-gear may be so connected with a brake-spindle or a brake-lever that the ordinary brake may be applied independently of the emergency-brake; or the vehicle may be partly or wholly stopped by the brake.

The construction of this brake is represented in the accompanying drawings, in which Figure 1 is an elevation showing this brake with an ordinary hand-brake. Fig. 2 is an end view of Fig. 1; Fig. 2^a, a disengaging mechanism for the rapidly-acting or emergency brake; Fig. 3, a plan of Fig. 1; Fig. 4, a modified form of the invention shown in Figs. 1 to 3; Fig. 5, a modification of the construction shown in Fig. 4, the brake-block acting from below; Fig. 5^a, a plan of Fig. 5.

This brake consists, substantially, of a brake-block, A, which, when the brake-lever is released, falls upon the front and top part of the periphery of the wheel, is driven forward by friction, and by a suitable arrangement of levers and connecting-rods causes the brake-block B very rapidly and with great force to be pressed against the rear part of the wheel, thus stopping the vehicle. The dotted lines show the position of the levers, brake-blocks, and connecting-rods when the apparatus is released.

The falling brake-block A is suspended in the bearing E, suitably placed on the under side of the vehicle-body on a lever, C, as in Figs. 1, 2, 3, or by a pair of levers, C² C², Fig.

5^a, and by means of the rod D, the rod D being pivoted at d and the lever C on pin e, the arrangement being such, as indicated in Figs. 1 and 2, that when the brake is "off" the lever 55 is nearly horizontal.

The cheeks of the brake-blocks B, which may be of beech, are fitted with a wrought-iron brake-shoe, b. A connecting-rod, F, Figs. 1 to 3, (or a pair of such rods, F² F², as shown 60 in Fig. 5^a,) serves to connect the brake-block A with the brake-block B, and the coupling-rod f connects the block A of one wheel, R, with the corresponding block of the second wheel, R', in the same pair, while a coupling-rod, f', connects the block B of one wheel, R, with the corresponding block of the other wheel, R', of the pair.

By the pivoted link or rod G, Figs. 1 to 3, or by a pair of such links, G' G', Fig. 5^a, connected with the coupling rod or rods f' and hung on pivots h in bearings H, the brake-blocks B are suspended from the under side of the carriage.

At the center of the coupling-rod f the brake-chain K is attached. The chain passes between k k and k' k', and is connected with the operating bar or rod J, the latter receiving the end of the chain K.

The mechanism for working the brake may 80 be of any suitable construction. For tram-cars it may be the following:

The operating-rod J has at the lower part a recess, i, with which the pawl i² engages. This rod is at the center of the front plate, L, of the 85 platform P of the car and held by straps, so as to be movable. A shoulder or projection, i³, on the rod J limits the movement of the latter.

To release the brake or "to put it on," the 90 driver pushes the pawl i² aside by means of his foot, and the weight of the blocks A A will cause the same to descend upon the wheel R R'. In consequence of effect the brake-blocks A A are driven forward by the wheels R R', 95 together with the lever C and bar D. The brake-blocks B B, impelled by the connecting-rods F F, together with the coupling-bars f' f', follow this motion, and thus are rapidly and forcibly applied to the wheels R R', where- 100 by the car is stopped. If, now, the falling block is raised off the wheel by rod J and

chain K, then the blocks B B will by their own weight and that of the rods G G fall away from the wheels R R'. The length of the rods F F is so chosen that the brakes are rapidly 5 put on; but no unpleasant or injurious jar or concussion can take place. With slight alteration this principle can be applied to railway-brakes also.

The construction of this emergency-brake is 10 such that it may be directly connected with a hand-brake spindle, so that either the blocks A and B may be simultaneously "put on" by one mechanism or the blocks B may be independently applied. To this end it is only necessary to key or fasten a lever, Z, on an extension, G', of the brake-bar *a* of the brake-blocks B, and to actuate said lever, say, by a bell-crank, *m n*, connected with brake-operating mechanism B' of the usual construction. Thus, 15 instead of the double emergency-brake, the blocks B may be worked by themselves by drawing the same against the wheels R R' by the aid of the rod Z and parts connected therewith. In the same manner the emergency-brake device can be put into operation by releasing the lever J. The chain O between the brake-spindle B' and the rod Z will not transmit the motion of the brake-blocks to the spindle B'; or, even in the case, while applying the 20 hand-brake, it should be found that more rapid action is required for arresting the vehicle in time, it will only be requisite to release the falling blocks A to cause quick action, as above explained.

25 In Figs. 4, 5, and 5^a is shown a modification of the rod-connections for the brake illustrated in Figs. 1 to 3, means being shown for working the falling brake-block either from above or from below.

30 The connecting-rod F is not directly connected with the brake-blocks A², as shown in Figs. 1 to 3, but is connected with and pivoted to the rod D², while the rod C² is attached to the block A² and the rod D². The action of the brake-block B² on the rod G² is substantially the same as that explained with reference to Figs. 1, 3.

35 In the modification shown in Fig. 5 the intermediary rod C² exerts additional pressure on the block A², thus increasing the effect.

40 The brake may be made to act by a brake-spindle, or an adjustable lever and block B² will be applied in a degree corresponding to the adjustment of A².

45 It will be obvious from the drawings that

one operating-gear and one lever or spindle 55 suffice to cause partial or entire application of the brake.

In the modification shown in Figs. 5 and 5^a the brake-block A² is made to act from below the chain, and other parts being arranged to 60 suit the motion of the wheel in the direction of the arrow.

I claim—

1. In a car-brake, the combination, with a 65 swinging brake-block arranged to bear on the periphery of one of the wheels at one side, of a gravity-block arranged to bear on the periphery of said wheel at the opposite side, the pivoted supporting-rod C, for said gravitational block, a connecting-rod for connecting the latter with the swinging block, and devices such as described for lowering and raising the gravitational block, substantially as and for the purpose specified.

2. In a car-brake, the combination, with a 70 swinging brake-block arranged to bear on the periphery of one of the wheels at one side, a gravitational block arranged to bear on the periphery of said wheel at the opposite side, a pivoted support for said gravitational block, a connecting-rod for connecting the latter block with the swinging block, and devices such as described for lowering and raising the gravitational block, of the lever Z, connected with the swinging block, the bell-crank lever *m* and *n*, 75 and appliances for actuating said bell-crank lever, substantially as and for the purpose specified.

3. In a car-brake, the combination, with a 80 swinging brake-block arranged to bear on the periphery of one of the wheels on one side thereof, a gravitational block arranged to bear upon the periphery of said wheel at the opposite side, and a pivoted support for the latter block, of a connecting-rod connected at one 85 end to the swinging block and at the other to the pivot for the support of the gravitational block, and devices, substantially such as described, for lowering and raising the gravitational block, substantially as and for the purpose specified. 90

In testimony that I claim the foregoing as my invention I have signed my name in presence of two subscribing witnesses.

ERNST FRIEDRICH WILHELM MÜLLER.
